FLEXIBLE EXTENSION MOP HAVING A PIVOTED FINGER MOP HOLDING MEANS

Henry H. Levin, Newark, N. J.

Application June 24, 1946, Serial No. 678,847

1 Claim. (Cl. 15—147)

1

This invention deals with improvements in the construction of mop-holders (as exemplified by U. S. patent to Schempp 1,821,481) in which the mop per se is detachably affixed to a flexible member capable of being retracted into the handle so as to be held rigid therewith, as in an ordinary mop, or to be extended as a flexible member to enable the mop at its extremity to be thrust under furniture without compelling the user to stoop to hold the rigid handle low enough for that purpose. As heretofore made, there are certain undesirable mechanical details of such an organization, which it is the aim of this invention to improve. The nature of my improvements appears in the accompanying drawings of my telescopic device, in which:

Figure 1 is a side elevation partly in section, showing the flexible member retracted to form a rigid handle.

Fig. 2 is similar to Fig. 1 except that the member is protruded to impart flexibility to the mop-holder.

Fig. 3 is a plan view, partly in section.

Figs. 4 and 5 are sections through lines x—x and z—z respectively of Fig. 1.

For the flexible member, a long flat spring A is proposed, having at its exposed extremity a mop-holding clip B and, at its housed extremity, a friction shoe C which is slidable within the bore of a tube D forming the lower part of a rigid handle; the upper portion of which may be a wooden stick E.

The tube D has a uniform diameter, except for its lower extremity, which is flattened at 1 to provide a slot-like exit for the flat spring A. The handle E is reduced at 2 to provide a seat for the tube which is thereby permanently attached thereto. The friction shoe C, which is secured to the upper end of the flat spring by a stud 3, consists of two semi-circular fiber friction blocks 4 and 5 which are recessed at 6 and 7 to house two open springs 8 and 9 which serve to maintain the blocks in frictional engagement with the bore of the tube and thus retain the flat spring A in any position that the user wishes to place it.

The lower end of the flat spring is curved hook-like, as indicated by 10, to provide a seat for the transverse twisted wires 11 of a conven-

tional mop. A washer or clip 12 is slotted to ride on the spring and normally closes the hook to retain in place the mop-wires. It is normally so held by a finger 13 pivoted to the flat spring by a bolt 14 and a spacer 15. This enables the clip to be backed off and the mop released for the ready substitution of a replacement when necessary.

It will be observed, from this disclosure, that this arrangement is sturdy and comprised of a minimum number of parts each of simple form; all promoting low cost in manufacture and resulting in a sturdy device conducive to long service.

15 I claim:

A telescopic mop-holder consisting of a tubular handle having an elongated circular bore terminating in a flattened end forming a slot-like exit; a friction block mounted within said bore and slidable from one end to the other thereof, said block comprising two semi-cylindrical shoes and a spring for urging them apart; an elongated flat spring having its one end secured to said friction block and its other end passing 20 through and protruding from said slot-like exit and having its extremity bent reversely to form a semi-circular hook; a mop having a twisted wire strand engaged by said hook; a washer slotted to slide on said flat spring; and a finger pivoted to said spring and adapted to be swung 25 through and protruding from said slot-like exit and having its extremity bent reversely to form a semi-circular hook; a mop having a twisted wire strand engaged by said hook; a washer slotted to slide on said flat spring; and a finger pivoted to said spring and adapted to be swung 30 towards said semi-circular hook and abut against the slotted washer to close the open side of the hook.

HENRY H. LEVIN.
